(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof showing the state that the subject design is completely unfolded;

FIG. 9 is a perspective view thereof showing the state that when folding the subject design in half, the back cover part

(Continued)

is pushed aside and then the transparent part on the front left side can be seen at the back side; and, FIG. 10 is a front view thereof showing an example of the usage of the subject design.

The appearance of the exterior in a fully opened position and the interior in a partially closed position forms no part of the claimed design.

1 Claim, 9 Drawing Sheets
